UNITED STATES PATENT OFFICE.

SEBASTIAN ZIANI DE FERRANTI AND GEORGE WALL, OF HOLLINWOOD, ENGLAND,
ASSIGNORS TO FERRANTI, LIMITED, OF HOLLINWOOD, ENGLAND.

ELECTRICITY METER.

Application filed January 21, 1921. Serial No. 439,008.

To all whom it may concern:

Be it known that we, SEBASTIAN ZIANI DE FERRANTI and GEORGE WALL, both subjects of the King of Great Britain and Ireland, 5 and both residing at Hollinwood, in the county of Lancaster, England, have invented certain new and useful Improvements Relating to Electricity Meters (for which we have filed an application in England January 17, 1920, Patent No. 165,133), of which the following is a specification.

This invention relates to the adjustment of electrical instruments including, for instance, integrating meters, indicating instruments and relays, and has for its object to provide simple and predetermined adjusting devices therefor.

The features of our invention which we consider novel and patentable are definitely 20 pointed out in the claims appended hereto.

Referring to the accompanying diagrammatic drawings:

Figures 1 and 2 indicate front and side views respectively of an induction integrating electricity meter in which are provided 25 separate low load, full load and inductive load adjustments according to the present invention.

Figures 3 and 4 are similar views of a 30 portion of a similar meter provided with modified full load and inductive load adjustments.

Figures 5 and 5^a represent details of a 35 modified low load adjustment.

Fig. 6 is a vertical section on the line 6—6 of Fig. 1.

In carrying the invention into effect in one 40 form illustrated by way of example in Figures 1 and 2 as applied to the usual adjustments desirable in an alternating current induction motor meter, we mount the series electromagnet *a* upon a hinged piece *b* for the purpose of effecting adjustment of the full load speed.

The heel of the hinged piece is provided 45 with a nut *c*, into which a screw *d* is fitted enabling the hinged piece to be rocked upon rotation of the screw. Beneath the screw head and between the heel and meter casing 50 is placed a strong compression spring *e* so that the hinged piece may be held rigidly in any position determined by that of the screw *d*.

The act of turning the screw is thus to 55 move the series electromagnet *a* farther

from or nearer to the shunt electromagnet *e*, thereby decreasing or increasing respectively the rotor speed.

Alternatively, the full load speed may be 60 adjusted by the movement between the retarding permanent magnets *f* of a piece of magnetic material *g*, say mild steel, (see Figures 3 and 4). Conveniently this magnetic material *g* is formed of flat section and is 65 mounted in bearings *h* carried by the permanent magnets, and at one end carries a projecting arm *i* of spring steel which itself is provided with a handle *j*. Beneath this handle is a peg which is capable of engaging in any one of a series of holes *k* formed 70 in the path of movement thereof.

This magnetic piece *g* is situated between the two permanent magnets *f* and by varying the position in which the handle *j* is placed, so the total retarding effect of the 75 permanent magnets is varied.

The positions of the holes *k* are such as to give, say, 1% adjustment from one hole to the next, the holes being, of course, formed 80 in a suitable plate *l* fitted between the permanent magnets.

The spaces between the holes *k* will be found to be non-uniform, being widest apart when the flat magnetic piece *g* is approximately parallel to the adjacent limbs of the 85 permanent magnets and being closest together when this magnetic piece is at right angles.

As regards the low load adjustment, we 90 use a piece of magnetic material *s* carried pivotally upon the centre limb of the shunt electromagnet *e* (Figure 1). This member is provided with a spring arm *t* carrying the handle *u* and peg capable of engaging any of a series of holes *v* in a convenient part of the 95 meter casing. Movement of this arm in a direction causing the magnetic piece to move away from its central or symmetrical position effects increase in low load speed for a given direction of rotation, and movement 100 of the lever in the reverse direction will effect a decrease in low load speed for the same direction of rotation. Alternatively we may fix a magnetic piece *m*, say of mild steel (see Figure 5), to a non-magnetic slide 105 bar *n* which is adapted to be moved laterally in relation to the shunt electromagnet *e*. This magnetic piece *m* is pressed into contact with the centre limb of the shunt magnet by means of small compression springs *o* (Fig- 110

ure 5^a) acting upon the non-magnetic slide *n*.

The slide is adapted to be moved by means of a screw *p* fitted to the meter frame and carrying an eccentric portion engaging a slot provided in the cranked end of the slide. This operating screw carries a small pointer *q* and a scale *r* mounted upon the slide serves to indicate the position in which the screw rests.

The magnetic piece *m* is thus capable of being moved towards or away from its central or symmetrical position by partial rotation of the screw *p*.

Upon the scale *r* are graduations so placed mutually as to give equal percentage adjustment between consecutive marks.

As regards adjustment for inductive load, we fix a conductor preferably in the form of a copper stamping *w* (as indicated in Figure 1) to a cranked slide piece *x*, the stamping surrounding the lower portion of the shunt magnet core. The cranked slide is provided with slots *y* engaging pins *z* fitted to the meter casing, compression springs (not shown) fitted beneath washers 6 (Figure 1) being carried on these pins and adapted to press the slide firmly against suitable surfaces on the meter casing.

At the lower end of the slide a slot 1 is provided with which an eccentric screw 2 engages. This eccentric screw operates the slide in a manner exactly similar to that described with reference to the low load adjustment indicated in Figures 5 and 5^a, a similar scale and pointer being provided in this case also.

In operation upon turning the screw 2 in one direction the slide *x* is lifted and the cranked end carrying the copper stamping *w* moved upwards in relation to the shunt magnet *e*. This upward movement of the copper stamping increases the speed on inductive load.

Movement of the screw in the reverse direction causes an opposite effect.

Alternatively as indicated in Figures 3 and 4, we may carry the copper stamping *w* upon a spring lever 3 pivoted to the meter casing; the spring lever in this case is provided with a knob 4 and peg, the latter engaging any hole of the series formed in a suitable part of the meter casing.

The retarding magnets are so disposed in relation to each other and to the rotor disc as to give a maximum braking effect. We are thus enabled to use a minimum quantity of steel for the desired speed of rotation.

It will be appreciated that by means of the adjustments according to the present invention the operation of calibrating the

meter is greatly simplified; e. g., assuming a meter has been tested and found to read 3% slow, then it is merely necessary to move the corresponding adjustment 3% in the opposite or fast direction when a substantially correctly reading meter is attained without the necessity for retesting.

Having now particularly described and ascertained the nature of our said invention and in what manner the same is to be performed we declare that what we claim is:

1. An electricity meter including a movable rotor element, a series electro-magnet 75 coil on one side thereof, a three-limbed magnetic core on the other side thereof, a shunt coil on the centre limb of said magnet core, a movable magnetic pole piece mounted adjacent said centre limb, and means for moving said movable pole piece across the field, thus effecting displacement of the magnetic field distribution as desired.

2. An electricity meter including a movable rotor element, a series electro-magnet 85 coil on one side thereof, a three-limbed magnetic core on the other side thereof, a shunt coil on the centre limb of said magnetic core, a movable magnetic pole piece pivoted upon 90 said centre limb, and means for rocking said movable pole piece laterally in the field, thus effecting displacement of the magnetic field distribution as desired.

3. An electricity meter including a movable rotor element, a series electro-magnet 95 coil on one side thereof, a three-limbed magnetic core on the other side thereof, a shunt coil on the centre limb of said magnetic core, a movable magnetic pole piece mounted upon a rockable arm pivoted upon said centre 100 limb, and an indicating scale co-acting with said arm.

4. Means for adjusting the full load setting of an electrical instrument including a movable electro-magnet mounted in proximity to a rotatable conducting member, and means for rocking said electro-magnet about a fixed axis in a direction substantially at right angles to the plane of the conducting 105 member.

5. An electricity meter including a movable rotor element, a series current electro-magnet core, supporting means for said core incorporating a carrying lug and a projecting lug, a fixed supporting lug, pivotal means connecting said supporting lug with said carrying lug and manually adjustable means coacting with said projecting lug to effect rocking of said supporting means.

In testimony whereof we have signed our names to this specification.

SEBASTIAN ZIANI de FERRANTI.

GEORGE WALL.
